[57] CLAIM

The ornamental design for a cigar holder, as shown and described.

DESCRIPTION

FIG. 1 shows a perspective view of the cigar holder of the present invention from the top, left and front;

FIG. 2 is a rear elevational view of the cigar holder;

FIG. 3 is a right elevational view of the cigar holder with the opposite view being a mirror image thereof;

FIG. 4 is a top plan view of the cigar holder; and,

FIG. 5 is a bottom plan view of the cigar holder.

The cigar holder as shown in brackets is of indeterminate length.
